UNITED STATES PATENT OFFICE.

RALPH R. JONES, OF LAKE FOREST, ILLINOIS.

BASKET-BALL BANK.

Application filed May 4, 1928. Serial No. 275,053.

This invention relates to improvements in basket ball bank, and one of the objects of the invention is to provide an improved metallic bank of this character which may be constructed of comparatively small gauge material, thereby reducing to a minimum the weight of the bank, and at the same time the bank will be of a rigid construction and will impart a lively rebound to the ball when struck by the latter.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

20 Figure 1 is a view in side elevation of an improved bank of this character constructed in accordance with the principles of this invention and showing the basket in position.

Figure 2 is a rear elevation of Figure 1, with 25 parts broken away and parts omitted for the sake of clearness.

Figure 3 is a detail sectional view, partly broken away, as taken on line 3—3, Figure 2.

Figure 4 is a detail view, partly broken 30 away, taken from the front of the bank.

In accordance with the principles of this invention the bank is formed from a single piece of sheet material 10 such as metal or the like of any desired gauge or thickness and may 35 be of any desired size and configuration according to the size of bank it is desired to form. The bank is preferably of a rectangular configuration and the edges 11 thereof are deflected rearwardly to form flanges which 40 encompass the periphery of the bank and serve to reinforce the same. The proximate ends of adjacent flanges are preferably mitered as at 12 and are secured together in any suitable manner such as by means of soldering 45 13, brazing or the like.

The front exposed surface of the bank 10 may be finished in any suitable manner either by painting, enameling or otherwise treating the same so as to produce a smooth and if desired a glazed surface.

50 Secured to the back of the bank and at any desired position so as to extend thereacross between the top and bottom flanges 11 are uprights 14 secured in position in any desired or suitable manner, either by spot welding, riveting or the like. These up-

rights 14 form braces and are preferably of angle iron construction, the upright edges 15 thereof being provided throughout their lengths with suitable apertures 16, for a purpose to be set forth.

Secured to the base portions 14 of the braces, in any suitable manner, and extending across the space therebetween is a brace or reinforcing member 17 also constructed of sheet material such as metal, and this member or brace 17 may be of any desired width and thickness. When the brace is secured to the base 14 of the upright braces, a space 18 will be formed between the front face of the brace 17 and the rear face of the bank 10.

70 A filler member 19 also of any desired size is arranged within the space 18 and is preferably disposed midway of the width of the bank 10. This filler member 19 may be secured in position in any suitable manner either by spot welding, brazing, riveting, or the like.

75 Apertures 20 are provided through the bank 10, filler member 19 and brace member 17 for the reception of anchoring members 21 such as bolts, which pass therethrough and these bolts serve as a means for securing the basket ring 21' to the front of the bank.

80 The ring may be of any desired configuration such for example as being provided with depending extremities 22 having deflected portions 23 which rest against the face of the bank. A filler member 24 to complete the ring 21' is arranged between the deflected portions 22 and is preferably of a U shaped configuration, the extremities 25 of the member 24 being deflected laterally so as also to rest against the face of the bank 10.

85 The extremities 25 are provided with apertures and the deflected portions 23 of the portions 22 of the ring 21 are also provided with apertures which register with the respective apertures 20 in the bank 10, filler member 19 and brace member 17 so that the fastening 90 bolts 21 may pass through the registering apertures, and nuts or collars 26 are provided on the bolts for removably securing the basket ring in position.

100 The usual basket 27 is supported by the ring 21'.

The bank is secured or supported in position in any suitable manner according to the accommodations of the place in which the bank is to be employed.

110 A simple and efficient means for supporting the bank embodies hanger rods 28 which

may be of any desired construction and are provided with threaded upper extremities 29 adapted to pass through a support or beam 30 and are secured thereto by means of fastening nuts 31 engaging the threads 29. The lower extremities of the rods 28 are preferably flattened as at 32 and the flattened portion of the rods rest against the faces of the respective upright brace members 15. Apertures are provided in the portions 32 of the rods which register with certain of the apertures 16 in the portions 15 of the upright braces 14, and fastening members 33, such as bolts or the like, pass through these registering apertures and secure the ends of the rods 28 to the upright braces 14.

Additional brace rods 34 are provided, one extremity of which is deflected as at 35 and is anchored to the ceiling 30 by means of fastening screws 36 passing through apertures in the portion 35 and into the ceiling. The lower extremities of these rods 34 may also be flattened as at 37 and are provided with apertures therethrough which register with certain of the apertures 16 of the portion 15 of the upright braces 14. Fastening bolts 38 are provided which pass through the registering apertures in the ends of the rods 34 and the upright braces.

With this improved construction it will be manifest that there will be provided a rigid bank and being constructed of metal, will impart a lively rebound to the ball. Furthermore, the bank being reinforced in the manner shown, will be of a rigid construction and may be formed of material of comparatively light gauge.

The filler member 19 co-operating with the reinforcing brace or member 17 and the front 40 of the bank will insure the rigidity of the ring 21.

With this improved construction it will also be manifest that the bank may be secured at any desired elevation or from any overhead support, the rods 28 and 34 being provided of the proper length to compensate the height of the support 30 above the ground.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A basket ball bank comprising a body portion formed of a single piece of sheet material, the periphery of said body being deflected to form a circumferential reinforcing flange, upright braces secured to the rear face of said body and within said flange, supporting rods secured by one end to said braces and by their other ends to a fixed support, and a basket ring secured to and projecting 60 beyond the front face of said body.

2. A basket ball bank comprising a body portion formed of a single piece of sheet material, the periphery of said body being deflected to form a circumferential reinforcing flange, upright braces secured to the rear 70 face of said body and within said flange, supporting rods secured by one end to said braces and by their other ends to a fixed support, a horizontal brace member secured to the first said braces and disposed in close proximity to the rear face of said body, a filler member between and engaging the proximate faces of the last said brace member and the bank, and a basket ring secured to and projecting beyond the front face of 80 said body.

3. A basket ball bank comprising a body portion formed of a single piece of sheet material, the periphery of said body being deflected to form a circumferential reinforcing flange, upright braces secured to the rear 85 face of said body and within said flange, supporting rods secured by one end to said braces and by their other ends to a fixed support, a horizontal brace member secured to the first said braces and across the space therebetween, said horizontal brace being disposed in proximity to the rear face of said body, a filler member between the last said brace and the rear face of said body, a basket ring adjacent the front of said body, and fastening devices for anchoring the said ring, said fastening devices passing through said body, filler member and said horizontal brace.

4. A basket ball bank embodying a body portion formed from a single piece of sheet material, a reinforcing flange encompassing the periphery of said body, vertical brace members secured to the rear face of said body 105 and projecting laterally therefrom, there being apertures through the said projecting portions of said braces, anchor rods, one end of which are secured to a fixed support, the other ends of said rods being disposed adjacent the said projecting portions of said braces, and fastening devices passing through said apertures and the adjacent extremities of said rods.

5. A basket ball bank embodying a body portion formed from a single piece of sheet material, a reinforcing flange encompassing the periphery of said body, vertical brace members secured to the rear face of said body and projecting laterally therefrom, there being apertures through the said projecting portions of said braces, anchor rods, one end of which are secured to a fixed support, the other ends of said rods being disposed adjacent the said projecting portions of said braces, fastening devices passing through said apertures and the adjacent extremities of said rods, a cross brace secured to the said vertical braces, spaced from and substantially parallel with the rear face of said body, 115 120 125 130

and a filler member in the space between said cross brace and the rear face of said body.

6. A basket ball bank embodying a body portion formed from a single piece of sheet material, a reinforcing flange encompassing the periphery of said body, vertical brace members secured to the rear face of said body and projecting laterally therefrom, there being apertures through the said projecting portions of said braces, anchor rods, one end of which are secured to a fixed support, the other ends of said rods being disposed adjacent the said projecting portion of said

braces, fastening devices passing through 15 said apertures and the adjacent extremities of said rods, a cross brace secured to the said vertical braces, spaced from and substantially parallel with the rear face of said body, and a filler member in the space between 20 said cross brace and the rear face of said body, there being apertures for anchoring a basket ring passing through said body, filler member and said cross brace.

In testimony whereof I have signed my 25 name to this specification, on this 27th day of April, A. D. 1928.

RALPH R. JONES.
